BRACELET CORD CLASP

Eugen Prestinari, Summit, N. J., assignor to
 Gemex Company, Newark, N. J., a corporation
 of New Jersey

Application July 7, 1936, Serial No. 89,319

10 Claims. (Cl. 24—265)

This invention relates to a fastening device and more particularly to a clasp for the bracelet cord of a wrist watch or the like.

One of the objects of this invention is to provide a clasp for the bracelet cord of a wrist watch or the like which is simple and sturdy in construction and pleasing in appearance. Another object is to provide a clasp of the above nature, the manufacture of which is readily accomplished with inexpensive materials. Another object is to provide a clasp of the above nature which may be easily operated by the user, and which securely clasps the end of a pliable cord. Another object is to provide a clasp of the above nature from which the end of the cord may be easily released. Other objects will be in part apparent and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing in which is shown two of the various possible embodiments of my invention,

Figure 1 is a bottom plan view of a bracelet cord, one end of which is secured in my clasp;

Figure 2 is a perspective view of my clasp;

Figure 3 is a sectional elevation taken along line 3—3 of Figure 2;

Figure 4 is a perspective view of the operating lever of the clasp;

Figure 5 is a perspective view of the gripping member of the clasp;

Figure 6 is a perspective view of the housing member of the clasp;

Figure 7 is an elevation of the gripping end of the link showing the operating lever and gripping member in folded or gripping position; and,

Figure 8 is a sectional elevation similar to Figure 3 of a modification of my clasp.

Similar reference characters refer to similar parts throughout the several figures of the drawing.

In order that certain features of my invention may be more readily understood, it might be well first to point out that numerous difficulties are encountered not only in the manufacture, but also in the operation of clasps for pliable bracelet cords or the like. Many of these clasps are inherently incapable of securely gripping or fastening the end or ends of a bracelet cord, while others, though able to securely grip the cord, can not maintain the grip with any degree of perman-

ency. Such clasps often readily become unfastened while in use, accordingly releasing the bracelet cord much to the inconvenience of the wearer and often to the damage of the watch to which the cord is secured. Still other clasps of this nature are characterized by considerable complication and multiplication of parts, necessitating extensive labor in their assembly because of the minute nature of the various parts. Still other clasps of this nature are quite fragile and often break under conditions of normal use. Some clasps, in order to overcome the disadvantages of fragility, are so cumbersome as to present an unattractive appearance when assembled with the bracelet cord and wrist watch. It is accordingly another object of this invention to rectify the above conditions in a thoroughly practical and efficient manner.

Referring now to the drawing, and particularly to Figure 1, a bracelet cord 10 has secured to one end 10a thereof in any suitable manner, a wrist watch 11. The other end of cord 10 is secured on fastening device generally indicated at 12, fastening device 12 preferably being attached to an expandible buckle or the like 9.

As better shown in Figure 2, clasp 12 comprises a housing generally indicated at 13 in which are pivotally mounted an operating lever generally indicated at 14 and a gripping member generally indicated at 15. Housing 13 (Figure 6) preferably comprises a substantially flat body portion 13a having a cut out portion 13b in one end thereof which forms a bar portion 13c or the like by which clasp 12 (Figure 1) may be secured to buckle 9. Extending upwardly from bottom portion 13a (Figure 6) of the housing are side portions 13d and 13e having formed therein respectively holes 16 and 17. Side portions 13d and 13e are also respectively provided with holes 18 and 19 which receive a pin 20 pivotally supporting gripping member 15 (see Figure 3). Pin 20 (Figure 6) also supports a coil spring 21, which is provided with ends 21a and 21b for a purpose pointed out hereinafter.

As is better shown in Figure 3, a stop or abutment 22 is formed on bottom 13a of housing 13 preferably directly to the right of opening 13b in housing bottom 13a, this stop being provided for a purpose disclosed hereinafter.

Referring now to Figure 4, operating lever 14 is preferably U-shaped in form, thus comprising legs 14a and 14b and a connecting portion or cross bar 14c. Preferably legs 14a and 14b are tapered in form, having formed in the small ends thereof arcuate portions 14d and 14e for a purpose pointed

out hereinafter. Extending away from and preferably integral with cross bar 14c, I provide a finger piece 42 by which the operating lever is actuated. As is better shown in Figure 3, cross bar 14c is preferably hook shaped. On the large ends of tapered legs 14a (Figure 4) and 14b of the operating lever, I provide pivot pins 23 and 24 which are preferably formed integrally with the legs. As is more clearly shown in Figure 2, pivot pin 23 5 extends through hole 17 in housing side or wall 13e. Pivot pin 24 (Figure 4) similarly lies within hole 16 (Figure 6) in housing wall 13d. Thus operating lever (Figure 2) is readily assembled in and is freely pivotable with respect to housing 13. 10

With reference to Figure 5, gripper 15 preferably comprises a top portion 15a from one end of which extend bifurcations 15b and 15c having secured thereto or formed integrally therewith eyelets 25 and 26 which preferably are coaxial and 15 spaced. Extending from the other end of the gripper top 15a is a suitably toothed gripping portion 15d having formed on opposite sides thereof shoulders 43 and 44, provided for a purpose pointed out hereinafter. I prefer to dimension 20 top portion 15a and gripping portion 15d of gripper 15 in such a manner that the width of these portions is slightly less than the distance between lever legs 14a and 14b so that when lever 14 and gripper 15 (see Figure 7) are in their folded or 25 secured position the gripper lies between the lever legs 14a and 14b. Also, gripping portion 15d of the gripper is so dimensioned that when in its folded or gripping position its toothed edge is 30 slightly spaced from bottom 13a of housing 13 35 (Figure 7).

Thus, as is more clearly shown in Figures 2 and 3, eyelets 25 and 26 are pivotally disposed on opposite end portions of pin 20 so that spring 21 lies between the eyelets. Thus gripper 15 is arranged in relation to spring 21 in such a manner 40 that end 21a of the spring bears against gripper top 15a while spring end 21b bears against housing bottom 13a to constantly urge gripper 15 upwardly into an open or nongripping position as 45 shown in Figures 2 and 3. Gripper 15, however, is limited in its opening movement by stop 22, which is preferably so proportioned as to permit the gripper to open sufficiently to enable the easy insertion of the end of bracelet cord 10 into housing 13 (see Figure 3). In this connection, it should be noted that the entry end (i. e. the right hand end of housing 13 as viewed in Figure 2) is substantially unobstructed due to the manner in which the pivotal mounting of operating lever 14 50 is effected. It should also be noted that stop 22 is so proportioned as to prevent gripper 15 from swinging out of the path of movement of operating lever 14. Otherwise the gripper, under the influence of spring 21, would swing into a relatively inaccessible position.

It may now be seen that operating lever 14 and gripper 15 are relatively pivotable and in order that these two parts may properly coact to secure the end of bracelet cord 10 within housing 13, it is 55 desirable that the holes 18 and 19 in housing walls 13d and 13e be spaced from holes 16 and 17 in the housing walls a distance substantially equal to the distance between the pivotal axis of operating lever 14 and a line drawn through the centers of arcuate portions 14d and 14e in lever legs 14a and 14b so that when the lever and gripper are folded down into housing 13, arcuate portions 14d and 14e fit over eyelets 25 and 26 on the gripper. Furthermore, I prefer to form operating lever 14 and 60 gripper 15 in such a manner that when they are

in their folded position, as shown in Figure 7, the tops of both are substantially flush with the top edges of housing walls 13d and 13e.

In operation, with reference to Figure 3, the end of bracelet cord 10 is inserted into the unobstructed gripping end of clasp 12. Thereafter, gripper 15 is forced downwardly with a clockwise movement as viewed in Figure 3, until its gripping portion 15d engages cord 10. Gripper 15 is held in this position while operating lever 14 is swung 10 downwardly with a counterclockwise rotation until lever legs 14a and 14b (Figure 2) engage shoulders 43 and 44 respectively on the gripping end of gripper 15. It may readily be seen that further counterclockwise movement of lever 14 (Figure 15 3) forces the teeth on the end of the gripper into biting engagement with cord 10, this movement of lever 14 being continued until its hook shaped cross bar section 14c snaps over the curved portion 15e of the gripper which joins gripper top 20 15a and bifurcations 15b and 15c. It may now be seen that during this latter movement of lever 14, the lower edges of lever legs 14a and 14b act like cams against gripper shoulders 43 and 44 to force the gripper into biting engagement with cord 10 25 wherein it is securely held by the resilient engagement between lever cross bar 14c and the curved end portion 15e of gripper 15. While the engagement between lever 14 and gripper 15 readily resists any casual forces tending to effect their 30 disengagement, these parts may be readily separated or opened by upward pressure of the fingernail under finger piece 42. Immediately upon disengagement of hook shaped cross bar 14c of the lever from curved portion 15e of the gripper, 35 spring 21 snaps the two pivoting parts into disengagement to permit easy removal of bracelet cord 10, stop 22 preventing gripper 15 from swinging out of the path of movement of operating lever 14.

It may now be seen that my clasp 10, although 40 simply constructed, is readily operable to grip efficiently the end of a bracelet cord.

Another embodiment of my clasp, shown in Figure 8, comprises generally an assembly of 45 parts similar in many respects both in construction and arrangement to the several parts comprising gripper 12 as shown in Figure 2. Accordingly, the clasp which is generally indicated at 30 in Figure 8 comprises a housing generally indicated at 31, which is substantially similar to housing 13 (Figure 6). Housing 31 thus pivotally mounts a gripper generally indicated at 32 and an operating lever generally indicated at 33; gripper 32 being urged upwardly 50 by the opposite ends of a spring 40 substantially similar to spring 21 (Figure 6). Extending upwardly from bottom portion 31a of the housing is a stop or abutment 34, which is positioned in relation to gripper 32 in substantially the same 55 manner as that of stop 22 and gripper 15 (Figure 3). Stop 34 (Figure 8), however, is preferably longer than stop 22 so as to limit the raising or opening action of gripper 32 to a greater extent than that of gripper 15, for a purpose described hereinafter.

Gripper 32 is provided with shoulders 32a, substantially similar to shoulders 43 and 44 of gripper 15 (Figure 5) and these shoulders coact 60 with legs 33a (Figure 8) of lever 33 as in the case of gripper 12. Legs 33a of lever 33, however, are preferably arcuate in shape along their gripper engaging edges, rather than tapered, so as to coact with gripper shoulders 32a in effecting 65 70 75

gripping engagement between the gripper and cord 10, as will be pointed out hereinafter.

Operating lever 33 is provided with a hook-shaped cross bar section 33b which, when lever 33 and gripper 32 are folded together, engages rounded gripper portion 32b to maintain the two parts in gripping position.

In operation, the end of bracelet cord 10 is inserted in housing 31 and operating lever 33 is swung in a counterclockwise direction as viewed in Figure 8. As stop 34 has limited the upward or opening movement of gripper 32, gripper shoulders 32a are so positioned as to be engaged by lever legs 33a at a point thereon where continued counterclockwise movement of lever 33 effects downward or clockwise movement of gripper 32 without the necessity of first forcing gripper 32 downward as in the case of gripper 12 in Figure 2. It may now be seen that continued counterclockwise or closing movement of lever 33 forces gripper 32 against the bias of spring 40 into biting engagement with cord 10 where it is held against casual displacement by frictional engagement between cross bar hook 33b of the lever with rounded portion 32b of the gripper. The gripper and lever are readily separated from their folded or gripping position by pulling upwardly against a finger piece 33c projecting from lever 33.

It may now be seen that while clasp 30 and clasp 12 are similar in many respects, clasp 30 is operated through manual actuation of the operating lever only, that is, in order to effect biting engagement between gripper 32 and cord 10 it is unnecessary to swing gripper 32 downwardly preliminary to engaging its shoulders 32a by the legs of lever 33. It may further be seen that gripper 30 may be rapidly and efficiently operated either to grip or release the bracelet cord, as the arcuate legs 33a of lever 33 are, in effect, cams against which gripper shoulders 32a act as followers during the operation of the lever to effect a secure clasp of the end of the bracelet cord. As in the case of clasp 12 (Figure 7) lever 33 and gripper 32 of clasp 30 (Figure 8) preferably fold together so as to lie substantially between the walls of housing 31 and accordingly present a substantially smooth surface.

Accordingly, I have provided a clasp for securing the end of a bracelet cord which fulfills the several objects and purposes pointed out hereinabove in a thoroughly practical and efficient manner.

As many possible embodiments may be made of the above invention and as many changes might be made in the embodiments above set forth, it is to be understood that all matter hereinbefore set forth, or shown in the accompanying drawing, is to be interpreted as illustrative and not in a limiting sense.

I claim:

1. In a device of the nature described, in combination, a housing adapted to receive the end of a pliable cord, a member pivotally associated with said housing and movable into gripping relation with said cord, a cam part pivotally mounted in said housing and swingable from a disengaged position into engagement with said member to force said member into its gripping position, said member being no longer than the distance between the pivotal axes of the member and said cam part and means for frictionally engaging said member to maintain said member in its gripping position.

2. In a device of the nature described, in com-

bination, a housing adapted to receive the end of a pliable cord, a gripping member pivotally mounted in said housing and pivotable into gripping engagement with said cord, and a substantially U-shaped operating member having its ends pivotally mounted in the cord receiving end of said housing whereby said cord receiving end of the housing is substantially unobstructed to permit the insertion of the cord end therein, said operating member including portions which engage portions of said gripping member to force said gripping member into gripping relation with said cord.

3. In a device of the nature described, in combination, a housing adapted to receive the end of a pliable cord, a gripping member pivotally mounted in said housing and pivotable into gripping engagement with said cord, a substantially U-shaped operating member having its ends pivotally mounted in the cord receiving end of said housing whereby said cord receiving end of the housing is substantially unobstructed to permit the insertion of the cord end therein, said operating member including portions which engage portions of said gripping member to force said gripping member into gripping relation with said cord, and means biasing one of said members toward a non-gripping position.

4. In a device of the nature described, in combination, a housing adapted to receive the end of a pliable cord, a gripping member pivotally mounted in said housing and pivotable into gripping engagement with said cord, a substantially U-shaped operating member pivotally mounted on said housing, said gripping member being provided with shoulders lying in the path of movement of said operating member during pivotal movement thereof whereby said operating member engages said shoulder and forces said gripping member into gripping relation with said cord, and means for maintaining said members in gripping relationship with said cord.

5. In a device of the nature described, in combination, a channel shaped housing, a gripper pivotally connected to the sides of said housing and adapted to lie therebetween when in gripping position, central portions of said gripper being narrower than the distance between the sides of said housing to provide a space between said gripper portion and one of the sides of the housing when the gripper is in gripping position, and a lever pivotally connected to a side of said housing and operable to force said gripper into gripping position, said lever being formed to fit into said space when said gripper is in gripping position.

6. In a device of the nature described, in combination, a channel shaped housing, a gripper pivotally connected to the sides of said housing and adapted to lie therebetween when in gripping position, portions of said gripper being narrower than the distance between the sides of said housing to provide spaces between said gripper portion and the sides of the housing when the gripper is in gripping position, and a U-shaped member having its legs pivotally connected to the sides of said housing and operable to close down on and hold said gripper in gripping position, the legs of said U-shaped member being formed to fit into said spaces when said gripper and said member are in gripping position.

7. In a device of the nature described, in combination, a channel shaped housing, a gripper pivotally connected to the sides of said housing and adapted to lie therebetween when in grip-

ping position, said gripper including a portion being narrower than the distance between the sides of said housing to provide spaces between said gripper portion and the sides of the housing when the gripper is in gripping position, a U-shaped member having its legs pivotally connected to the sides of said housing and operable to close down on and hold said gripper in gripping position, the legs of said U-shaped member being formed to fit into said spaces when said gripper and said member are in gripping position, and spring means constantly biasing said gripper toward non-gripping position.

8. In a device of the nature described, in combination, a housing formed to receive the end of a pliable cord, a gripping member pivotally mounted in said housing including a portion movable therewith into a position within the walls of said housing to grip said cord, the walls and bottom of said housing being substantially coextensive, and an operating member pivotally secured to said housing and movable from a disengaged position into engagement with said gripping member to close down on and hold said gripping member portion in gripping engagement with said cord, said operating member having spaced portions which lie on opposite sides of and embrace said gripping member when both of said members are in gripping relationship.

9. In a clasp for gripping a pliable bracelet cord or the like, in combination, a channel-

shaped housing, a gripper member pivotally connected to said housing and adapted to grip said cord, and a lever pivotally connected to said housing at a point substantially spaced from said gripper member closely adjacent one end of said housing, said lever being pivotable towards said gripper to engage and move said gripper into gripping position, the pivotal axis of said lever being spaced above the pivotal axis of the gripper.

10. In a device of the nature described, in combination, a housing adapted to receive the end of a pliable bracelet cord, said housing having side walls connected by a web portion, a gripping member pivotally mounted in said housing between said side walls and pivotable from a position outside of said housing into said housing toward said web portion to grip said cord, and an operating member pivotally connected to said housing between said side walls near the end of said housing, the pivotal axis of said operating member being substantially spaced from said web portion whereby the cord receiving end of the housing is substantially unobstructed to permit the insertion of the cord end therein, said operating member having portions which engage portions of said gripping member to force the gripping member into gripping relation with said cord.

EUGEN PRESTINARI. 30
